UNITED STATES PATENT OFFICE.

MARY TOBENER, OF GOLD HILL, NEVADA.

FABRIC-FOLDING ATTACHMENT FOR SEWING-MACHINES.

SPECIFICATION forming part of Letters Patent No. 511,977, dated January 2, 1894.

Application filed July 26, 1893. Serial No. 481,524. (No model.)

To all whom it may concern:

Be it known that I, MARY TOBENER, a citizen of the United States, and a resident of Gold Hill, in the county of Storey and State 5 of Nevada, have invented certain new and useful Improvements in Sewing-Machine Attachments; and I do hereby declare the following to be a full, clear, and exact description of the invention, such as will enable others skilled in the art to which it appertains to 10 make and use the same.

This invention relates to sewing machine attachments of that class known as folder or seam finishers, and has for its object to fold 15 or finish a seam by a simple construction and arrangement of parts, which are readily attachable or detachable to and from a sewing machine.

With this and other objects in view, the 20 invention consists of the construction and arrangement of the several parts, which will be more fully hereinafter described and claimed.

In the drawings: Figure 1 is a perspective 25 view showing the improved attachment applied in operative position. Fig. 2 is a perspective view of the attachment disconnected, and shown on a larger scale. Fig. 3 is a section on the line $x-x$ Fig. 2. Fig. 4 is a 30 transverse section on the line $y-y$, Fig. 6. Fig. 5 is a detail perspective view of a piece of fabric which has been folded by the attachment. Fig. 6 is a side elevation of the device.

Similar numerals of reference are employed 35 to indicate corresponding parts in the several figures.

Referring to the drawings, the numeral 1 designates an arm, having a loop or sleeve 2 at one end thereof, in which is fitted a removable fastening screw 3, having a portion 40 of its shank smooth and not threaded. This construction is for the purpose of securing the attachment to a sewing machine but it is to be understood that no stress is to be laid 45 upon this arrangement, as any preferred means may be employed for applying the attachment. The arm 1 is positioned in the proper plane and at the proper angle to ac-

commodate the attachment and operation of the device, and at its free end is secured a conical shaped folding sleeve 4, with a slot 5 extending the full length of one side thereof. Within the said conical sleeve is a divider 6, formed by inturning the edges of the said sleeve 55 on the side opposite that to which the slot is formed, and the said divider stands away from the side of the sleeve in which the said slot is located. The divider extends through the larger end of the sleeve and 60 throughout its length it partakes of the same degree of width proportionately to the increase of the width of the said sleeve from its smaller toward its larger end. The end of the divider which projects through the sleeve is 65 separated and the two parts are bent laterally in opposite directions at slight oblique angles to provide folders or formers 7.

The fabric to be folded has the two edges thereof placed in the slot 5 and is turned 70 and fed to the needle and simultaneously connected to produce the form shown in Fig. 5. It will be seen that this finishes a seam and makes a strong connection without the use of binding. When the two pieces of fabric are inserted in the slot, the edge of each is caused to assume a position on opposite sides of the divider, and as they are drawn under, are turned inward or under, and in this condition are ready to be seamed by the 75 machine.

The attachment entire is simple and effective in its construction and operation, is easily manufactured, and can be readily applied or detached. It is adapted to be used 80 in connection with any form or make of machine, and the essential feature of the invention resides in the conical sleeve and the divider therein of the nature set forth.

Having thus described the invention, what 85 is claimed as new is—

In a sewing machine attachment for the purpose set forth, a conical sleeve suitably supported having a dividing partition secured to one of the inner sides of the sleeve 90 and extending toward the opposite inner side thereof, said divider extending through and projecting outwardly from the larger end of

said sleeve and tapering proportionately to the taper of the sleeve, with the parts of said free projecting end extended laterally in opposite directions, said sleeve directly opposite the dividing partition having a slot extending throughout the length thereof, substantially as described.

In testimony whereof I have signed this specification in the presence of two subscribing witnesses.

MARY TOBENER.
